S. J. Cox

UNITED STATES PATENT OFFICE.

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

STOVE-LEG CONNECTION.

Application filed June 18, 1927. Serial No. 199,657.

The improvements relate to stove frames and supports, and primarily to the frames and legs of modern gas and electric stoves, in which the parts are usually made of sheet metal or sheet metal and castings combined, and they have for their principal objects the production of a stove leg and frame connection which may be manufactured and assembled at a low cost for labor and materials and will be strong, durable and efficient in use.

The improvements are illustrated in the accompanying drawings referred to herein, in which

Fig. 1 is an inside perspective view of a corner of the stove frame and leg with connections embodying the improvements, a portion of the frame bottom being broken away to expose the leg top and connecting parts beneath;

Fig. 2 is a vertical section substantially on the line 2—2 of Fig. 1;

Fig. 3 is a plan of the inside corner member; and

Fig. 4 is a side elevation of the leg.

The frame 1, which I prefer to make of sheet metal, has its lower edge 2 turned up to form a deep groove 2' receiving the bottom edge of the downwardly turned flange 3' of the corner bottom 3, and also to make a strong reinforced bottom edge for the frame, but this is not essential in all cases, as the said bottom is supported on the inturned upper flange 5' of the corner piece 5, and may be welded, bolted or otherwise secured thereto, and by means of its depending flange to the frame or housing 1 of the stove.

The bottom 3 may be of triangular form, as shown, or of any other form, and may extend as far as desired over the bottom opening of the frame to close the same wholly or partly and support a removable bottom or tray. In the construction shown it is welded to the horizontal top flange 5', by spot welds, and thus reinforces and is supported and reinforced by the said flange.

The corner bracket 5 has offset wings 5" in contact with the depending flange 3' of the corner bottom, so that the vertical body portion of the bracket is spaced from said flange to receive the upstanding and angular flange 6' of the leg 6, which is locked in position by set screws or bolts 7 passing through 5 and having conical inner ends received in small recesses 6" in the said leg

flange. In this manner the leg, which in the construction shown is a casing, and the stove frame, which is of sheet metal, are secured together rigidly and firmly, and reinforced against all separating strains. The angular form of the flange 6', however, corresponding with the form of the frame, and the fact that it fits snugly into the space between 5 and 3' give the connection sufficient strength and rigidity to resist all ordinary strains, and even to hold the parts together when the stove is lifted from the floor or other support and prevent the leg from falling out. The wings 5" are preferably welded to the flange 3', and are forced in between it and the upturned bottom edge 2, when that construction is employed.

The shoulder formed at the top of the leg where it joins its flange 6' provides a secure support for the stove frame and as the said flange is wedge shaped in cross section the weight of the stove tends to make the connection between it and the supported stove frame tight.

In assembling the parts the corner bracket 5 should first be placed in position, the bottom then placed thereon and welded thereto if desired, and the wings welded to the depending flange of the bottom through the walls of the frame. If desired, however, the parts 3 and 5 may be first secured together and then placed in the corner of the frame. The upstanding top flange of the leg is then passed in between the flange 3' of the bottom and the depending portion of the corner bracket 5, and the set screws tightened, if they are employed.

It will be seen from the foregoing that the parts of the leg and connection may all be made up separately in such a manner that they may be assembled without cutting or shaping of any description, and that the work and materials involved in these operations is relatively small and the resulting structure extremely strong and dependable.

What I claim is:

1. In a stove leg connection, a leg proper having a flange at its top, a frame member and a bracket secured together and having spaced portions to receive the leg flange, said members supporting a bottom member which is connected therewith.

2. In a stove leg connection, a leg proper having an angular flange at its top, a frame

- member and a bracket member secured together and having angular spaced portions to receive the leg flange, said members supporting a bottom angular member which is connected therewith.
3. In a stove leg connection, a leg proper having a flange at its top, a frame member and a bracket member secured together and having spaced portions to receive the leg flange, said members supporting a bottom member which is connected therewith, said frame member having a turned-up bottom portion forming a recess to receive a part of the bracket member.
4. In a stove leg connection, a leg proper having an angular flange at its top, a frame member and a bracket member secured together and having angular spaced portions to receive the leg flange, said members supporting a bottom angular member which is connected therewith, said frame member having a turned-up bottom portion forming a recess to receive a part of the bracket member.
5. A separable stove leg and frame connection comprising an angular frame member, having on its lower part an angular bracket member with a portion in spaced relation thereto to form a sheath for a leg connecting member, a leg and a leg connecting member extending upwardly therefrom and adapted to be received in said sheath.
6. A separable stove leg and frame connection comprising an angular frame member, having on its lower part an angular bracket member with a portion in spaced relation thereto to form a sheath for a leg connecting member, a leg and a leg connecting member extending upwardly therefrom and adapted to be received in said sheath, and means for locking the said parts together.
7. A separable stove leg and frame connection comprising a frame member, having on its lower part a bracket member with a portion in spaced relation thereto to form a sheath for a leg connecting member, a leg and a leg connecting member extending upwardly therefrom and adapted to be received in said sheath, the said portion of the leg being wedge shaped and adapted to be held in the sheath by frictional coaction.
8. In a stove leg connection, a leg proper having a flange at its top, a frame member and a bracket member secured together and having spaced portions to receive the leg flange, said members supporting a bottom member which is connected therewith, said bracket member comprising a strip of metal secured to the frame member at spaced points and out of contact therewith intermediate such points so as to form a bracket or sheath.
9. In a stove leg connection, a leg proper having a flange at its top, a frame member and a bracket member secured together and having spaced portions to receive the leg flange, said members supporting a bottom member which is connected therewith, said bracket member comprising a strip of metal secured to the frame member at spaced points and out of contact therewith intermediate such points so as to form a bracket or sheath and adjustable fastening means adapted to engage a leg member connected with the first named members.
10. In a stove leg connection, a leg proper having a flange at its top, a frame member and a bracket member secured together and having spaced portions to receive the leg flange, said members supporting a bottom member which is connected therewith and adjustable fastening means adapted to engage a leg member connected with the first named members.
11. A separable stove leg and frame connection comprising a bent frame member defining an upstanding wall having on its lower and inner part a bent bracket member with a portion in spaced relation thereto to form a laterally extending sheath for a leg connecting member, a leg having a body portion and a leg connecting member extending laterally beyond said body portion and adapted to be received in said sheath.

Witness my hand this 13th day of June, 1927, at the city of Milwaukee, in the county of Milwaukee, State of Wisconsin.

EDWIN A. RUTENBER.
